UNITED STATES PATENT OFFICE.

W. DEAN SMITH AND J. THEODORE GURNEY, OF BOSTON, MASSACHUSETTS.

PLATFORM-WAGON.

SPECIFICATION forming part of Letters Patent No. 242,800, dated June 14, 1881.

Application filed March 28, 1881. (No model.)

To all whom it may concern:

Be it known that we, W. DEAN SMITH and J. THEODORE GURNEY, citizens of the United States, residing at Boston, in the county of 5 Suffolk and State of Massachusetts, have invented certain new and useful Improvements in Platform-Wagons; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a perspective view of our improved platform and gear. Fig. 2 is a top or plan view of the same.

20 B B' are the upper and lower members of elliptic springs, one at either end of the axle, 25 and secured thereto by any usual or approved construction of clip or other fastening.

25 C is a bearer, its ends being secured to the central part of the upper members, B', of the springs, and provided at c c' with mortises to receive the futchels or hounds D and the lower member of the fifth-wheel I. As said fifth-wheel may be of any usual or approved construction, it need not be described specifically any further than to say that its lower member 30 is to be firmly attached to the bearer C, and that g is a clip employed to secure together the two members of the fifth-wheel; and two or more such clips may be used at opposite or suitable points of the wheel. These futchels are provided at their front end with hinge-like joints, to which the thills are to be attached. They extend rearwardly through the bearer C upon converging lines, and may be attached to each other at their rear ends.

35 E is a bolster, corresponding substantially to the bearer C, except that its position is inverted, its upper and outer ends receiving the body of the wagon. It is mounted upon the upper member of the fifth-wheel, and is firmly 40 attached thereto. The upper central portion of the bearer C and the lower central portion of the bolster E are in close contact, by preference.

45 F are carriers seated centrally in mortises formed for their reception in the bolster E. The front ends of these carriers are curved up-

wardly to form supports for the foot-board F'. They are also provided with downwardly curved or inclined projections, which rest upon the upper member of the fifth-wheel at f. 55 These carriers are arranged upon converging lines, their rear ends approaching or adjoining each other.

G is a bearing-block seated between the rear ends of the carriers F, and serving to partially support the body of the wagon, and also to counterbalance the weight of the foot-board, and the driver when resting thereon, thus relieving the joint formed at the point where the carriers pass through the bolster E. By preference we extend the lower central portion, G, of the bearing-block and attach it to the upper member of the fifth-wheel, thus distributing the weight of the wagon-body and of the driver in such manner that it is thrown upon 70 the upper member of the fifth-wheel at five points.

H H are steps, which are attached to the front ends of the futchels or hounds by means of bolts in the upper ends, h, of the shanks of 75 the steps.

Although we prefer to use a fifth-wheel in the form of a complete circle, yet we do not wish to be limited to such construction, because many of the advantages of our platform-gear will be derived from the employment therewith of a semicircular fifth-wheel, when arranged either in front or in rear of the bearer and bolster.

When preferred, the construction and arrangement of parts may be such that the futchels may intercept the bearer at points nearer to its center than those shown, and thereby be made to support the fifth-wheel at points farther in front of the axle than is shown, and 80 such construction may be found especially desirable where a semicircular fifth-wheel, arranged in front of the bearer and bolster, is employed.

It will also be seen that in consequence of 95 the futchels extending rearwardly from the bearer C and beneath the lower member of the fifth-wheel, their rear ends are supported against upward thrust to resist the downward pressure upon their forward ends which is 100 produced when the driver places his weight upon the steps H, which construction and ar-

angement serves to prevent the parts from undue strain.

What we claim is—

The combination, with the bearer C, of the futchels D, provided at their front ends with a step or steps, H, and supported at their rear ends against upward thrust, substantially as set forth.

In testimony whereof we affix our signatures in presence of two witnesses.

W. DEAN SMITH.
J. THEODORE GURNEY.
